UNITED STATES PATENT OFFICE.

CHARLES L. EDWARDS, OF DALLAS, TEXAS.

DESIGN FOR A BADGE.

SPECIFICATION forming part of Design No. 22,637, dated July 18, 1893.

Application filed May 9, 1893. Serial No. 473,632. Term of patent 7 years.

To all whom it may concern:

Be it known that I, CHARLES L. EDWARDS, a citizen of the United States of America, residing at Dallas, in the county of Dallas and 5 State of Texas, have invented and produced a new and original Design for a Badge; and I hereby declare the following to be a full, clear and exact description of my invention, such as will enable others skilled in the art 10 to which it appertains to make and use the same, reference being had to the accompanying drawing which forms a part of this specification, wherein—

The figure is a plan of the top surface of my 15 design, the representations as hereinafter described being in relief.

The leading features of my design consist of a circular disk having an interior field concentric therewith on which is a represen-

tation of a grass-covered field on the slope of 20 a hill-side *a*; a dismounted cannon *b* at the base of said hill; two cannon shells *c*, *c*, near the muzzle of said cannon; three muskets *d*, stacked in military style over said cannon; a plow *e* to the rear of said muskets, a representation of the setting sun *f*, to the left and beyond the hill, and two five-pointed stars 25 *g*, *g*, oppositely arranged on the rim of said design, as shown in the drawing.

Having described my invention, what I 30 claim as new, and desire to secure by Letters Patent, is—

The design for a badge as herein described and shown.

CHARLES L. EDWARDS.
